UNITED STATES PATENT OFFICE.

GEORGE W. CHENICEK, OF WHITING, INDIANA, ASSIGNOR TO STANDARD OIL COMPANY, OF WHITING, INDIANA, A CORPORATION OF INDIANA.

SEAL.

Application filed November 17, 1924. Serial No. 750,325.

To all whom it may concern:

Be it known that I, GEORGE W. CHENICEK, a citizen of the United States, residing at Whiting, in the county of Lake and State of Indiana, have invented a new and useful Improvement in Seals, of which the following is a specification.

The present invention relates to improvements in seals or vent valves, more particularly as applied to the vent pipes from the vapor spaces of gasoline storage tanks and storage tanks for like volatile liquids. It will be fully understood from the following description illustrated by the accompanying drawing, in which:

Figure 1 is a vertical sectional view longitudinally through a valve or seal construction embodying the present invention;

Fig. 2 is a horizontal sectional view on the line 2—2 of Fig. 1; and

Fig. 3 is a vertical sectional view on the line 3—3 of Fig. 1.

The seal of the present invention is an improvement on the construction of the seal shown in the prior application of H. V. Atwell Serial No. 715,765, filed May 24, 1924.

Referring more particularly to the drawings, the numeral 5 indicates a vertical vent pipe section which communicates with a vent pipe (not shown) from a storage tank. The vent pipe section 5 is surrounded by a pan 6 of rectangular horizontal section, with suitable outwardly flaring sides 6^a. Two upstanding lugs 7 secured to the top of the vent pipe section 5 carry a horizontal pivot rod 8, upon which is pivoted the inverted rectangular cup 9, the sides of which surround the upper end of the vent pipe section 5. The inverted cup 9 is of sufficient depth so that its sides enter a body of liquid suitably maintained in the pan 6. The inverted cup 9 is constructed upon the same principle as shown in the prior application of Atwell previously referred to; that is, the center of gravity is offset with respect to the center of pressure. The portion of the inverted cup on one side of the pivot rod 8 is greater in the area of its bottom surface than the portion on the other side, the latter being weighted as at 10 to bring the center of gravity directly over the pivot rod 8. With this construction, as is readily apparent,

when the sides of the inverted cup 9 are immersed in liquid in the pan 6, an excess of pressure within the vent pipe 5 will tend to cause one end of the cup 9 to rise, that end being, in the form shown in the drawing, the portion on the right of the pivot rod 8. When the pressure within the vent pipe 5 is reduced below that of the exterior atmosphere, reverse action takes place, the side of the inverted cup 9 having a larger area being depressed.

In the construction shown, means are illustrated for effectively damping rocking movement of the inverted cup in its operation.

As shown in the drawings, the ends 10 of the inverted cup 9 which are parallel to the pivot rod 8 are cut away from their centers to each side as at 11 to form openings of gradually decreasing area as the ends respectively descend into the liquid present in the pan 6. The sides are similarly cut away, as at 11^a. As a result of this construction, as either end of the pan is forced down into the liquid, a gradually decreasing aperture for the escape of air is provided, thereby preventing the escape of air from within the top by a sudden rush, with resulting rocking of the cup.

To further prevent rocking or bobbing of the inverted cup in its operation, and likewise to control the pressure under which the cup operates to open the vent, weights 12 in the form of flat bars extending across the pan 6, are suspended at their corners by suitable flexible cords 13 from swivels 15, which are, in turn, suspended from adjusting screws 16 secured in the top of the inverted cup 9 on opposite sides of the pivot 8. The screws 16 are adjusted so that the weights 12 barely rest upon the bottom of the pan 6 when the cup 9 is balanced and level. By suitable adjustment of the weights 12, the force required to raise either end of the inverted cup 9 may be independently controlled. The weight on the rising side of the pivot is lifted and determines the amount of pressure, that on the descending side resting upon the bottom of the pan 6 and exerting no force in consequence.

A suitable protecting cover 17 may be provided, being supported by lugs 18 on the upper edge of the pan 6.

Although the present invention has been

described in connection with the specific details of a device for carrying the invention into effect, it is not intended that these details shall be regarded as limitations upon the scope of the invention, except in so far as is suited in the accompanying claims.

I claim:

1. A seal comprising an open conduit member communicating with a vapor space, 10 a pan surrounding said conduit member and adapted to contain a liquid, an inverted cup over said conduit member and having its sides immersed in the liquid in the pan, said cup having its center of pressure offset from its center of gravity, means for pivotally supporting said cup at substantially its center of gravity, the cup being formed at each end with openings tapered upwardly, flat weights suspended in a substantially horizontal plane from said cup from each side of its center of gravity, said weights being 15 maintained in a plane substantially hori-

zontal and touching the bottom of the pan when the cup is substantially level.

2. A seal comprising an open conduit member communicating with a vapor space, 20 a pan surrounding said conduit member and adapted to contain a liquid, an inverted cup over said conduit member and having its sides immersed in the liquid in the pan, said cup having its center of gravity offset from its center of gravity, means for pivotally supporting said cup at substantially its center of gravity, the cup being formed at each end with openings tapered upwardly, flat weights suspended in a substantially horizontal plane from said cup from each side of its center of gravity, and means for 25 adjusting said weights so that they touch the bottom of the pan when the cup is substantially level.

GEORGE W. CHENICEK.
